UNITED STATES PATENT OFFICE.

LOUIS T. BRISCOE, OF SANDYHOOK, CONNECTICUT.

NECK-YOKE ATTACHMENT.

SPECIFICATION forming part of Letters Patent No. 730,088, dated June 2, 1903.

Application filed April 8, 1903. Serial No. 151,637. (No model.)

To all whom it may concern:

Be it known that I, LOUIS T. BRISCOE, a citizen of the United States, residing at Sandyhook, county of Fairfield, State of Connecticut, have invented a new and useful Device for Attaching Neck-Yokes to Wagon-Poles, of which the following is a specification.

My invention has for its object to provide a relatively inexpensive, safe, durable, and attractive looking device for attaching a neck-yoke to the pole of a wagon, it being required in a device for this purpose that all complications be avoided, leaving the device as simple as possible, that it be quick and certain in operation and absolutely reliable, that any appearance of clumsiness be avoided, and that the device be so constructed as to render it impossible for the reins to catch under the end of the pole.

With these and other objects in view the invention consists in certain constructions and in certain parts, improvements, and combinations, which will be hereinafter described and then specifically pointed out in the claims hereunto appended.

In the accompanying drawings, forming part of this specification, Figure 1 is a plan view illustrating the operation of my novel neck-yoke attachment, and Fig. 2 is a sectional view corresponding therewith.

My novel neck-yoke attachment comprises, essentially, a cap-piece fixed to the end of the pole and provided with a socket and a clip encircling the neck-yoke centrally and provided with an oscillatory swivel-pin adapted to engage the socket in the cap-piece.

10 denotes the pole, affixed to the end of which is the metallic cap-piece 11, having a socket 12 extending inward from the end thereof.

13 denotes the neck-yoke, 14 a clip affixed to the neck-yoke centrally, and 15 a swivel-pin which is adapted to engage the socket in the cap-piece and is provided with a head 16, pivoted between ears 17, extending inward from the clip and adapted to oscillate in the horizontal plane, a bolt 18 extending downward through both ears and the head and being retained in place by a nut 19.

50 In order to prevent the possibility of detachment of the neck-yoke from the pole in

use, I preferably provide a safety-strap 20, one end of which is secured to the clip, the other to the inner end of the cap-piece, as by screws 21, which pass through holes in the 55 clip and cap-piece, respectively, and engage the wood of the neck-yoke and pole. This safety-strap is preferably made in two parts, one of which is provided with a buckle 22, one part remaining permanently with the 60 pole, the other with the neck-yoke in case it should be required to shift neck-yokes, it being wholly immaterial so far as the principle of the invention is concerned whether the neck-yoke remains permanently attached to 65 the pole or is detached therefrom and hung up with the harnesses.

The operation will be so obvious as not to require description, the use being precisely the same as other devices of the same character, the important features being that the pole does not project outward beyond the neck-yoke, but the neck-yoke is carried outside of the pole, so as to render it impossible for the reins to engage, and, furthermore, that 75 the neck-yoke is retained in such a manner that all rattling is avoided, the yoke being free to oscillate on the head of the swivel-pin in the horizontal plane and the swivel-pin, with the neck-yoke, being free to oscillate 80 in the vertical plane, so that while ample freedom of movement of the neck-yoke is provided for there is an entire absence of looseness and rattling.

Having thus described my invention, I 85 claim—

1. A neck-yoke attachment comprising a cap-piece inclosing the end of the pole and having a socket extending inward, a clip to engage the neck-yoke centrally and a swivel- 90 pin pivoted to the neck-yoke and adapted to engage the socket.

2. A neck-yoke attachment comprising a cap-piece inclosing the end of the pole and having a socket extending inward, a clip inclosing the neck-yoke centrally and having inwardly-extending ears and a swivel-pin having a head pivoted between the ears so as to adapt it to oscillate in the horizontal plane, said swivel-pin being adapted to oscillate in 100 the socket.

3. A neck-yoke attachment comprising a

cap-piece for the pole having a socket extending inward from the end, a clip engaging the neck-yoke centrally, a swivel-pin pivotally connected thereto and engaging the 5 socket and a safety-strap one end of which is attached to the neck-yoke, the other to the pole.

In testimony whereof I affix my signature in presence of two witnesses.

LOUIS T. BRISCOE.
